UNITED STATES PATENT OFFICE.

JOHN R. KLIN, OF DAYTON, OHIO, ASSIGNOR TO THE RIKE FOLDING BOX COMPANY, OF DAYTON, OHIO, A CORPORATION OF OHIO.

CLIP.

Original application filed July 26, 1926, Serial No. 124,929. Divided and this application filed November 23, 1926. Serial No. 150,349.

My invention relates to garment bags and in particular to a self-opening garment bag and is a division of my application Serial No. 124,929 filed July 26, 1926.

5 It is the object of my invention to provide a self-opening garment bag which will stay in open condition for the insertion of the garments.

10 It is a further object of my invention to provide such self-opening mechanism which will also serve as a support for the garment hangers and will enable a plurality of such hangers and garments thereon to be placed in the bag, thus increasing the capacity of the 15 bag.

It is a further object of my invention to provide a novel form of clamp or means for clamping the open sides of the bag to form a tight enclosure.

20 Referring to the drawings:

Figure 1 is an end elevation of the bag blank;

Figure 2 is a plan view of the blank;

25 Figure 3 is an end elevation of the bag in closed condition;

Figure 4 is a section on the line 4—4 of Figure 3;

Figure 5 is a plan view of the new form of clamp of my invention;

30 Figure 6 is a side elevation thereof;

Figure 7 is a perspective of the clip with the tape being removed.

Referring to the drawings in detail, the blank is composed of a series of rectangular sections for the front panel, designated 1, 2, 3 and 4. An upper overlapping flap 5 is provided and a lower flap 6. A double folding flap consisting of sections 7 and 8 is provided on the free edge which is adjacent the 35 mouth of the bag. The rear wall of the bag is formed into a series of rectangular sections 9, 10, 11 and 12 corresponding to the sections 1, 2, 3, and 4. On one of these rear sections is mounted a plate of paper 13 which is saturated with a compound to prevent moths and other insects from disturbing the clothing in the bag. The free edge which is adjacent the 40 side mouth of the bag is provided with a folding flap consisting of the sections 14 and 15 which cooperate with the sections 7 and 8 for closing the mouth of the bag.

On this flap there is located by tapes 16 the

clamps 17 which clamp the folds along the mouth of the bag to seal the bag. It is generally preferable to have one of these clamps 55 to each one of the panels as the bag folds along the line 18 which separate the respective panels.

The reason for the folding of the bag in this particular fashion will be hereinafter explained.

For purposes of general reference to the bag as a whole, the rear of the bag will be designated 19 and the front of the bag 20.

When the bag is folded, it will be observed 65 that the flaps are folded one over the other to form a compact structure, better illustrated in Figure 4, over which the clamp is slipped. This clamp consists of a U-shaped member having the legs 21 and 22. It is made of 70 spring steel. The leg 22 is longer than the leg 21 and is upturned at its end, as at 23, so that that end will overlap the folded end 24 of the folded edges of the bag.

This extreme end is also provided with a 75 wedge-shaped slot 25 terminating in an eye 26 in which is located the supporting tape 16. This particular form of eye is such that the relatively broad tape cannot pass out through the narrow exit opening from the eye 26 to 80 the wedge-shaped slot 25 unless the tape has been especially manipulated so that there is no possibility of the clips falling off of the bag when once mounted.

To demount the clips from the tapes it is 85 necessary to place a portion of the tape in the wedge-shaped slide and then move the tape into the eye pulling the end of the tape through the eye and out of the clip, as in Figure 7.

Having thus fully described my invention, what I claim as new and desire to secure by Letters Patent, is:—

A new article of manufacture for use as a clamping clip on a garment bag consisting of 95 a U-shaped spring member having one arm forming an arcuate inwardly extending overlapping portion having an eye and wedge-shaped opening communicating therewith with its narrowest portion at the eye being 100 adapted to receive a supporting tape through said opening and in said eye.

In testimony whereof, I affix my signature.
JOHN R. KLIN.
